UNITED STATES PATENT OFFICE

SAMUEL WITMER, OF TOLEDO, OHIO.

MACHINE FOR GRINDING VARIABLE CURVES.

995,393.

Specification of Letters Patent. Patented June 13, 1911.

Application filed December 27, 1909. Serial No. 535,068.

To all whom it may concern:

Be it known that I, SAMUEL WITMER, a citizen of the United States, and a resident of Toledo, in the county of Lucas and State 5 of Ohio, have invented a certain new and useful Machine for Grinding Variable Curves; and I do hereby declare the following to be a full, clear, and exact description of the invention, such as will enable 10 others skilled in the art to which it appertains to make and use the same, reference being had to the accompanying drawings, and to the figures of reference marked thereon, which form a part of this specification.

15 My invention relates to grinding machines and particularly to machines for grinding variable curves on refractors and reflectors for the purpose of avoiding spherical aberrations, but is not restricted to such use as 20 it may be employed for any purpose or in any connection for which it may be adapted or appropriate.

The object of my invention is the provision of an apparatus of this class, which is 25 efficient and economical in its operation and construction, and which will produce in a simple and practical way substantially any of the curves required by the laws of refraction and reflection.

30 The invention is fully described in the following specification, and while in its broader aspect it is susceptible of embodiment in numerous forms, a preferred form and a few modifications of the same are illustrated in the accompanying drawings, in which,

Figure 1 is a side elevation of the preferred form of my machine adapted for grinding substantially the parabolic curve 40 with portions in section and broken away. Fig. 2 is a cross-section on the line $x-x$ in Fig. 1. Fig. 2^a is a side edge view of a slightly modified form of the grinding-tool. Fig. 3 is an enlarged elevation of a modified 45 form of the grinding mechanism adapted for grinding curves of less variation than a parabolic in case of a concave, and of greater variation than a parabolic in case of a convex. Fig. 4 is a front elevation of the grinding mechanism in Fig. 3. Fig. 5 is a diagram illustrating the changes which the work undergoes during different grinding operations. Fig. 6 is a plan of another form 50 of my invention adapted for grinding curves of greater variation than a parabolic in case

of a concave and curves of less variation than a parabolic in case of a convex. Fig. 7 is a side elevation of the same with portions broken away, and Fig. 8 is an end elevation thereof, with a part in section.

Referring particularly to Figs. 1 and 2 of the drawings, 1 designates the table of the machine frame and 2 the supporting legs or standards therefor. Mounted in suitable bearings in the table 1 and a subjacent 60 frame part 3 are a plurality of vertical spindles, which are arranged in a common vertical plane, and, in the present instance, shown as being three in number, the two outer ones being designated 4, 4 and the 65 inner or central one 5. These spindles are mounted for longitudinal adjustment in their bearings, which adjustment is effected by adjusting screws 6, one of which is threaded through each bracket 7 carried by 70 the frame part 3 and has its inner end bearing against the lower end of the associated spindle to form a pedestal bearing therefor. Each of the spindles 4, 4 carries a gear 8 in mesh with a gear 9 on the center spindle 5, 80 the latter gear having its periphery preferably broadened to adapt the gears to remain in mesh during a relative adjustment of the shafts, as is apparent. One of the spindles 4 has a spiral or worm gear 10 feathered 85 thereto and meshing with a drive worm 11, which is carried on a shaft 12. This shaft is journaled in suitable bearings at one end of the machine frame and is shown as carrying a belt-pulley 13, but power may be com- 90 municated thereto in any other suitable manner. The worm-gear 10 is held against axial movement by the frame-part 3, on which it is shown as resting, and by the casting or part 14, which extends over the worm-gear 95 and has its ends attached to said frame part. Each of the spindles 4 carries a stock 15 at its upper end, which stock is shown as being removably fitted over the tapered end of the spindle to facilitate a tight fitting of the 100 same on the spindle and at the same time an easy removal of the same therefrom. This stock has its top broadened or suitably shaped to support a templet or pattern 16, which is preferably held in position there- 105 on by a surrounding collar 17 in co-operation with interposed rubber or other suitable form of gasket member 18 and a suitable cementitious substance. The collar 17 is preferably provided at its outer edge with an up- 110

wardly projecting flange to form a cup shape member around the pattern for the purpose hereinafter described.

The spindle 5, which is the work carrying 5 spindle, has a stock 19 removably fitted over its tapered upper end to revolve therewith, such stock having its upper end approximately the diameter of the work 20 intended to be supported thereby, and fashioned to 10 provide a suitable seat for the work, as indicated. Threaded to the upper portion of this stock is a collar 21, which adjustably supports a ring or collar 22 of preferably the same material as the work or of like 15 hardness. The ring or collar 22 is intended to fit closely around the rim of the work and has its top fashioned to form a continuation of the curved surface of the work, whereby the grinding tool or medium, hereinafter 20 referred to, is enabled to overreach the edges of the work in its abrading movements and to end its strokes on the ring 22 rather than on the work itself, as the latter would cause an unevenness in the work surface at the end 25 of the strokes. The work and ring being of the same material or hardness wear down together so that their top surfaces or lines are always coincident. The collar 21 and ring 22 are encircled by a collar 23 and interposed gasket member 24, the collar 23 having its outer edge formed with an upwardly 30 projecting flange to form a receptacle or cup around the work to hold the abrasive material and the particles worn from the work in 35 the grinding or abrading operations. The securing of the parts of the holder together in this manner enables the cup-rings 23 to be quickly removed to clean the same. I wish it understood, however, that both the pattern 40 and work holders may be constructed in any other suitable manner.

Disposed above the pattern and work holders of the machine is a tool carrying frame 25 which is shown in the present instance as comprising the two transversely spaced parallel bars or side pieces 25' having the connecting end pieces 26, 26, to which the plates 27 forming shoes for riding on the templets or patterns 16, 16, are secured, as by the coöperating action of the 45 screws 28, and clamping plates 29. The plates or shoes 27 may be adjusted vertically between the clamping members as may be desired to compensate for wear, and stand in 50 planes parallel with the spindle axes. The clamping faces of the pieces 26 and 29 should be flat.

Rising from the bars or sides of the tool 60 carrying frame adjacent an end thereof are the arms or uprights 30 which have the vertically spaced bars or links 31, 31, projecting therefrom toward the center of the frame. These bars are pivotally attached at their outer ends to a vertically-disposed tool carrying head or member 32, to one side of

which is clamped an abrading or grinding tool 33, by the coöperating action of the clamping plate 34 and screws 35. It is thus apparent that the head 32 and abrading tool are permitted to freely rise and fall in a 70 vertical plane due to its link connection with the arms 30, as indicated. The lowering movement of the tool head is limited, however, by a stop 36, which is adjustably carried by said head and adapted to coact with 75 a subjacent part of the frame 25, as indicated.

The abrading tool 33 is intended to rest freely upon the work 20 and to have horizontal abrading movements with the frame 80 25 and independent vertical movements with its carrying head. This tool stands in a plane parallel to the spindle axes and is preferably of flat thin blade form of a sufficient width to preferably extend across 85 about four-fifths of the work, but is not restricted to this width as it may be more or less as working conditions may require. The working edge of the tool longitudinally conforms to the intended or desired shape of the 90 work surface, whether such shape be of convex or concave form, and in thickness is preferably much less than one-eighth of the diameter of the work. It is apparent, however, that the tool in working over an irregular surface may have its working surface changed slightly while reducing the irregularities, but the work and tool ultimately and naturally correct each other until the parabolic curve desired is substantially reached. While the tool is shown as being of thin blade form, it may have its body thickened and its working edges reduced as indicated in Fig. 2^A.

When the work is being ground to a pattern or patterns, as shown in Fig. 1, the patterns 16 have their working surfaces of the shape which it is desired to impart to the work, and the shoes 27 of the frame, have their working edges of the same general 105 contour as the abrading tool 33 or of a shape to fit the surface of the pattern on which it rides, and are substantially of the same thickness as said tool. It is thus apparent that on a reciprocation of the frame 25, as 110 hereinafter described, such frame will rise and fall as the shoes pass forward and backward over the patterns 16 and the abrading tool 33 will rise therewith due to the stop 36 resting on the frame and will lower by gravity or in any other suitable manner. A permissible vertical movement 115 of the tool 33 relative to the frame 25 is important, however, as it enables the tool to rise and fall independent of the frame 25 when passing over irregularities in the work surface not present in the patterns. Such movement of the tool also permits it to grind surfaces without the guidance of 120 the patterns, as the stop 36 may be removed 125 130

or the tool-head elevated free from the frame to permit the tool to follow the surface of the work and to gradually change the shape of the same to substantially a 5 parabolic curve. Or in other words, the purpose of the patterns is merely to grind a plurality of articles to the same curvature. If, however, uniformity of curvature of different pieces of work is not important 10 a multiplicity of articles may be ground in the same operation by placing separate work pieces on each spindle in lieu of the patterns 16 and employing the shoes 27 as grinding tools. It is apparent that the patterns 15 and shoes may be made to correct their respective shapes or to grind each other to substantially parabolic curves by placing a suitable abrasive material in the cups formed by the collars 17 of the pattern-holders. 20

The reciprocatory movements are imparted to the frame 25 from the oscillations of a lever 37, which is carried by a shaft or stud at the end of the table 1 opposed to 25 the drive-shaft 12, and has its upper end in connection with the frame 25 through the medium of one or more rods 39. The lower end of this lever is connected by a rod 40 to a crank-pin 41 carried by a disk 42 on the 30 shaft 12. The crank-pin 41 is shown as being adjustable radially of the disk 42 to change the length of stroke of the frame 25 and the lower arm of the lever 37 is shown as comprising two relatively adjustable 35 parts which permit of a change in the position of the frame 25 relative to the spindles 4-5, whereby the movements of the tool and shoes may be centered relative to the parts on which they respectively work. 40

The relative rotary movements of the spindle 5 and the reciprocatory movements of the frame 25 are preferably such that the frame will make approximately 54 strokes to one revolution of the spindle, as this is 45 found in practice to be a proper ratio. It is not desired, however, to restrict the relative movements of these parts to any particular ratio as it may be changed as desired.

The operation of this form of my machine 50 is as follows:—Preparatory to grinding the surface of a lens or other article, whether of concave or convex form, templets or patterns 16 are secured within the holders carried by the spindles 4, 4 and the lens or other 55 work is secured within the holder carried by the spindle 5 with the collar or ring 22 surrounding it and forming a continuation of the surface to be ground. Should the patterns 16 and shoes 27 not have their co- 60 acting surfaces of like form the machine is operated for a time before placing the work therein so as to mutually correct the surfaces for the patterns and shoes, a suitable abrasive material being placed within the cups 65 with the patterns to facilitate such action.

The patterns and work being in position in their respective holders and the former in proper condition, the frame 25 is placed over the same with the shoes 27 thereof resting in proper position on the patterns and the 70 abrading tool 33 resting in proper position on the work, as indicated. The spindles are also vertically adjusted to permit the tool to rest freely on the work with its stop 36 nearly in contact with the frame 25 when 75 the shoes 27 are resting on the patterns. The drive-shaft 12 now being thrown into motion imparts slow rotary movements to the spindles 4, 5 through the medium of the worm 11, worm-gear 10, and gears 8 and 9, 80 to cause the patterns and work to turn slowly under their respective contacting parts, and communicates the requisite reciprocatory movements to the frame 25 and attached parts through the medium of the 85 crank-disk 42, rod 40, lever 37 and rods 39. The tool 33 in moving backward and forward over the work gradually reduces it to the shape of the patterns and when this is accomplished the stop 36 rests on the 90 frame 25 and supports the tool-head to prevent further reduction of the work. The tool 33 finishes its strokes upon the collar or ring 22 to avoid any roughness at the edge of the work. Should 95 it not be important to maintain an exact conformance between different pieces of work, a plurality of the same may be ground in one operation by placing separate work pieces on each spindle, and employing the 100 shoes 27 as grinding tools. When the work and tool conform to each other throughout the entire stroke of the tool, the required parabolic curve has been substantially 105 formed and the grinding operation may then be stopped. The shoes and tools are shown as being reversible to adapt either end of the same to be used. During a grinding operation the grinding edge of the tool always stands at right angles to its stroke. 110

In the modification shown in Figs. 3 and 4, which is adapted for grinding surfaces to curves of less variation than a parabolic in case of a concave, and to curves of greater variation than a parabolic case of a convex, 45 designates the table or frame of the machine, 46 the work-spindle, 47 the stock of the work-holder, 48 the collar threaded thereto, 49 the work embracing collar or ring, which is of like material or hardness 115 to the work, 50 the cup-forming collar, 51 the gasket between the collar 50 and the collars 48 and 49, and 52 the work.

A standard 53 rises from the table 45 at one side of the work-holder and has an arm 54 120 projecting therefrom over the work. This arm is mounted for vertical adjustment relative to the standard, due to the bolt 55 carrying the arm working through a longitudinal slot 56 in the standard. A block or 125

guide member 57 is pivoted to the outer end of the arm 54 by a bolt 58, or in any other suitable manner, for vertical oscillatory movements, and reciprocally working 5 through a guide opening in such block or member is the vertically-disposed arm 59 of a tool-carrying head 60. Clamped to one side of this head by a plate 61 and coöperating screws 62 is an abrading tool 63 of 10 the form of machine described for grinding substantially parabolic curves. This tool when in vertical position stands substantially over a diametrical line of the work, and when oscillated by a reciprocatory 15 movement of the attached rod 64 is adapted to move first in one direction and then the other over the work surface with the axis of the block 57 as its pivot.

In grinding a convex surface the pivot 20 58 may be vertically adjusted by an adjustment of the arm 54 on the standard 53 to secure a greater or less departure from a parabolic curve, as the nearer the pivot to the work surface the greater the departure 25 from the parabolic curve. When the pivot of the grinding tool is placed without the center of curvature of the work, when working on a concave surface, it grinds a curve which substantially coincides with the short 30 or end curve of an elliptic circle, and when placed within the center of curvature of the work it produces a curve which substantially coincides with the long or side curve of an elliptic circle.

35 I will now describe the form of my invention disclosed in Figs. 6, 7, and 8, which is adapted for grinding curves of greater variation than a parabolic in case of a concave, and of less variation than a parabolic 40 in case of a convex. In this form 65 designates the machine frame or table; 66 the work-supporting spindles; 67 the adjustable pedestal supports or screws therefor; 68 the work-holders carried by the spindles, which 45 holders may be of similar construction to the holders in the preferred form of the machine, or of any other suitable form; 69 the meshing gears on the spindles; 70 the drive-shaft; 71 the worm for driving a 50 worm-gear (not shown) on one of the spindles; 72 the tool carrying frame, which superimposes the work-holders; and 73 the lever which is connected at one end to the tool-frame by the link member 74 and at its 55 other end to the crank 75 on the drive-shaft by the rod 76. The frame 72 is shown in the present instance as being of rectangular form, and as carrying a tool-carrying head 77 above each work-holder. Blades or tools 60 78 of the form previously described are clamped to these heads in a suitable manner. The end heads 77 are pivotally hung within the frame 72 by pivot studs or screws 79, while the center or intermediate head or 65 heads, if more than three be employed, is

shown as being pivotally hung from the ends of arms 80, which are pivoted at their opposite ends to the frame 72 as at 81. The purpose of this is to permit the end heads and tools to have vertical movements relative 70 to the center head and tool, as two supports for the frame would always rest on the work while a third would tend to raise one of the tools from the work if the different pieces of the same are not uniform. In order to cause the tools when moved backward and forward with the frame to assume the angle with reference to the work surface which the curves to be produced may require, I provide each tool-head with an arm 80 85 82, which projects outwardly from an end thereof in a plane with the grinding tool and at one side of its pivot in the frame 72, and has its free end angled to form the vertically disposed part 83. This part has 85 its free end portion working loosely through a guide opening in a swivel-block 84, which is pivoted to a carrying-block or part 85. The blocks 85 are shown as being vertically adjustable on a graduated slide 86 to produce greater or less variations in the surface curvatures of the work. Either convex or concave surfaces may be ground with this form of machine by simply changing the 90 shape of the tool. The operation of this 95 form of my invention is apparent.

In Fig. 5 the line *a a* represents the spherical curve of a convex piece of work before being ground; the line *b b* represents the spherical curve of a concave piece of work 100 before being ground, and the heavy line *c c* represents the form of the curve of the finished work. The spaces between the light lines and the heavy line represent the portions which are ground away in obtaining 105 the desired form of curve.

It is apparent that I have provided a machine and attachments therefor, which render the production of variable curves simple and easy and avoids much of the difficulty 110 encountered in other methods, principal among such objections being the presence of circles on the surfaces of ground articles. It is also apparent with this construction that the tools and work mutually act to correct each other, and when the tools and work 115 conform in curvature throughout the entire stroke of the former the desired curve is produced.

While I have shown the employment of 120 three spindles for carrying the work or the work and patterns, it is obvious that any number of such spindles may be used, and that all may be used for carrying work or a portion utilized for carrying patterns 125 when the work is being ground to patterns. I also wish it understood that I do not limit myself to the use of the particular form of grinding tool shown and described, but intend my invention to cover the use of any 130

tool having a broad thin grinding edge. I further wish it understood that my invention is not limited to any specific construction or arrangement of the parts except in so far as such limitations are specified in the claims.

Having thus described my invention, what I claim as new and desire to secure by Letters Patent, is,—

10 1. In a machine of the class described, the combination of a rotatable work-support, an abrading tool adapted for reciprocatory movements across the work transverse to its turning axis, said tool completing its 15 strokes without the zone of the work, and mechanism for actuating the movements of the tool and work-support.

2. In a machine of the class described, the combination of a rotatable work-support, 20 port, an abrading tool adapted to rest for free vertical movements upon the work and to have reciprocatory movements across the surface of the same, said tool having a long thin working edge conforming longitudinally to the desired cross-sectional curvatures of the work surface, and mechanism 25 for rotating the work-support and reciprocating the tool across the same.

3. In a machine of the class described, the 30 combination of a work-support having a part adapted to closely surround the work, said part being of equal hardness with the work, and an abrading tool reciprocally movable across the work and completing its 35 movements upon such part.

4. In a machine of the class described, the combination of a rotatable work-support, mechanism having an abrading part movable across work carried by said support in 40 a plane transverse to the turning axis of the support, and means coöperating with said mechanism to limit the abrading action of said part on the work.

5. In a machine of the class described, the 45 combination of a rotatable work-support, mechanism having an abrading part reciprocally movable across work held by the support, rotatable patterns conforming in shape to the desired shape of the work co-operating with said mechanism for controlling the abrading action of such part on the work, and means for rotating the work-support and patterns.

6. In a machine of the class described, the 55 combination of a rotatable work-support mechanism having an abrading part reciprocally movable across work held by the support and provided with a long thin working edge, rotatable patterns coöperating with said mechanism to control the abrading action of said part, and means for rotating the work-support and patterns.

7. In a machine of the class described, a 60 vertically adjustable rotatable work-support, mechanism having an abrading part recip-

rocally movable over work held by the support vertically adjustable patterns coöperating with said mechanism to control the abrading action of said part, and means for rotating the work-support.

70

8. In a machine of the class described, the combination of a vertically adjustable rotatable work-support, mechanism having an abrading part adapted to freely rest on the work held by the support and reciprocally movable over the same, vertically adjustable rotatable patterns coöperating with the mechanism to control the abrading action of said part, and means for rotating the work-support and patterns in unison.

75

9. In a machine of the class described, a plurality of spindles, work-holding means carried by same and patterns carried by others of said spindles at their upper ends, means for rotating said spindles, a frame 85 disposed over said work-holding means and patterns, shoes carried by said frame and riding on said patterns, an abrading tool carried by the frame and adapted to rest freely on work held by said holding means, and means for moving the frame to impart reciprocal movements to the shoes and tool across the parts on which they ride.

80

10. In a machine of the class described, a plurality of rotatable members, templets carried by a part of such members and work carried by another part of such members, a frame having parts working on said templets to guide the movements of the frame, an abrading element carried by said frame 100 and working over the work, and mechanism for rotating said members and imparting reciprocatory movements to said frame.

95

11. In a machine of the class described, the combination of a plurality of rotatable 105 parts, templets carried by a part of said members and work carried by the others of said members, a frame capable of reciprocatory movements over said members and having parts riding on said templets, an abrading member carried by said frame for free vertical reciprocatory movements relative thereto and capable of riding on the work, and mechanism operative to reciprocate said frame and impart rotary movements to said 110 members.

110

12. In a machine of the class described, the combination of a plurality of rotary members, templets carried by a part of said members and work carried by the other part 120 of said members, a frame reciprocally movable over said members and having blade-like parts resting upon said templets for reciprocatory movements thereover and having their working edges conforming to the 125 contour of the templets, a part carried by said frame for limited vertical reciprocatory movements relative thereto and adapted to normally rest upon the frame, an abrading tool carried by said part for acting on the 130

work, said tool having a long thin working edge conforming to the desired cross-sectional contour of the work surface, and mechanism for rotating said members and 5 imparting reciprocatory movements to said frame.

13. In a machine of the class described, rotatable work-holding means comprising a spindle, a stock carried by such spindle, such 10 stock having its upper end approximately the diameter of the work to be operated on and fashioned to provide a seat therefor, a collar threaded to the stock, a ring supported by said collar and surrounding the 15 edge of the work with its top fashioned to form a continuation of the upper work surface, said ring being of a material of substantially equal hardness with the work, and a second collar adjustably mounted upon 20 said first collar and coöperating therewith to hold said ring in position.

14. In a machine of the class described, the combination with a rotatable work sup-

port, of mechanism having an abrading part reciprocally movable across work held by 25 the support and having a long thin working edge, said part making a plurality of strokes across the work at each complete rotation of the support.

15. In a machine of the class described, 30 the combination of a rotatable work support, an abrading tool mounted for reciprocatory movements across the work and having a long thin working edge with its length transverse to its stroke and mechanism for 35 rotating the work support and moving the abrading tool, the tool having a plurality of strokes to each complete rotation of its support.

In testimony whereof I have hereunto 40 signed my name to this specification in the presence of two subscribing witnesses.

SAMUEL WITMER.
